HEEL-BUILDING MACHINE AND METHOD.

Application filed August 14, 1920. Serial No. 403,536.

This invention relates to building heels comprising a plurality of superposed lifts of predetermined characteristics. The invention is herein set forth by way of illustration with special reference to the building of so-called pasted or wet heels, although in various aspects the invention is not so limited.

It has been customary in practice to build such heels manually, the heel lifts usually being sorted and placed in bins or lift holders in accordance with the size, form, quality or other characteristics of the lifts. Commonly a single heel form or mold conforming to the desired shape and size of the heel to be built is located on a table in front of the heel lift holders and a paste tank provided with suitable paste-applying means, such as a paste pad or brush, is disposed near the heel form. The operator successively removes the lifts, one at a time, from the holders, applies paste to such lifts as are to be coated and deposits or assembles the lifts successively in predetermined positions in the heel form until the heel of the desired height is built.

In order to speed up these naturally slow manual operations, operators frequently use both hands at once, one hand reaching for and removing the lifts singly from the lift holders while the other hand is used for paste applying and for positioning the lifts in the heel form as they are taken from the lift holders. Although heels may be built more rapidly by this procedure, the operator's attention is necessarily divided between the lift holders, the pasting apparatus and the heel form. None of the operations receives full and undivided attention and the resulting confusion and consequent nervous, mental and physical fatigue incident to such an inherently inefficient procedure inevitably result in carelessness, inaccuracy and inferior quality of the product. Moreover, the relative location and arrangement of the lift holders, the pasting apparatus and the heel form is such that there are many useless and wasteful motions required in transferring the lifts from the holders to the pasting apparatus and thence to the heel form, particularly when lifts are taken from the more remote holders, making it necessary to shift the lifts from one hand to the

other before they are pasted or assembled. Even under the most favorable conditions, therefore, and if performed in the best manner possible, the method heretofore practiced is inefficient and wasteful of time and energy.

After heels are built in the general manner indicated, they are usually subjected to light pressure in some form of heel-press and maintained under such pressure for a considerable period of time until the paste has substantially set. Jack-presses for holding a pile of heels under pressure are commonly employed, although various well-known forms of heel-presses are also utilized. Whatever the character or type of press used, however, the prior art presses have uniformly subjected heels to light pressures only, these pressures being as low even as 20 pounds and not exceeding, so far as known, 100 or at most 125 pounds, with the result that pressure periods of not less than 20 minutes to one half an hour and many times extending to 10 or 12 hours have been required for the setting of the paste.

One of the objects of the present invention is so to provide for building heels by hand that heels of uniformly high quality may be built much more rapidly, economically and efficiently and with a minimum amount of effort and skill upon the part of the operator.

In the preferred exemplification of the present invention herein described by way of illustration, to obviate the above mentioned and other disadvantages of prior procedures, heels are built in multiple by performing at each of several stations, in turn, operations upon a plurality of heels substantially concurrently, as by substantially similar operations of the two hands of the operator, the operations at each station preferably being completed before the attention and effort of the operator are transferred to the succeeding station.

In the production of wet or pasted heels, the lifts of each heel, except the first lift, are coated with paste before they are placed in a heel form and, preferably, the lifts which are concurrently assembled, are transferred together and subjected to substantially concurrent heel pressure. Thus, although a plurality of heels are built at the same time,

the movements of the operator are coordinated and the attention and effort of the operator are focused upon one operation at a time. Preferably the heel lift holding means, the pasting means and the heel forms are relatively constructed and arranged for substantially continuous movements of the lifts in the same general direction from the holding means to the heel forms.

10 As shown, the lift holding means are constructed and arranged for ready removal of a plurality of lifts at the same time and the paste pad or brush, if one is used, may be constructed and arranged to permit the 15 operator to apply paste to a plurality of lifts substantially concurrently, while the lifts are still retained in the operator's hands, as by a wiping movement of the lifts over the pasting means, the excess paste 20 then being removed and the remaining paste distributed, as by pressure upon a flat surface.

Another object of the invention is to provide for improved pressing of heels in such 25 manner that, without sacrifice of general utility, the pressing of heels so built substantially concurrently and in multiple may be facilitated. In this aspect, the invention 30 contemplates pressing such heels while other heels are being built in other heel forms. This is accomplished in the illustrated heel 35 building machine by two sets of heel forms, each of which sets comprises duplex heel forms that cooperate with pressure means, the construction and arrangement being such 40 that one set of heel forms is out of alignment with the pressure means while the other set of heel forms is in cooperative pressing relation thereto. As shown, relative movement of one set of heel forms and the pressure means to apply substantially 45 concurrent pressure to the heels built in said forms, and relative movement of the other set of heel forms and the pressure means out 50 of pressing relation and into position for the ready assembling of lifts in the heel forms of that set are effected alternately and substantially concurrently by mechanism under the control of the operator.

55 A further object of the invention is to provide a method of heel manufacture which shall produce heels of uniformly superior quality in which the component lifts are thoroughly and firmly stuck together, and by 60 reason of which method the paste in the heel sets under pressure with great rapidity.

To this end, the freshly pasted and assembled heels are immediately subjected to 65 very heavy pressure for a short period of time. The amount of pressure and the length of time during which the pressure is applied, are more or less variable, depending upon the character of the paste and other conditions. The pressure is, however, greater- 70 ly in excess of the pressures heretofore uti-

lized in heel-processes of the prior art, and the duration of the application of pressure is greatly reduced.

By experiment, it has been found that pressures in the neighborhood of 1600 lbs. applied for approximately a half a minute, produce heels which are extremely strong and well stuck together, although pressures ranging from 500 lbs. up to 2400 lbs. or thereabouts, and applied for a period even 75 as short as 15 seconds have been determined to be effective in producing heels of a quality superior to those of the prior art. While, in the practice of this invention, the amount of pressure and the duration of its application 80 may be inversely varied to an extent so that the period of application of pressure may be shortened if greater pressure is applied, in any event the heavy pressures provided by the present invention attain their 85 maximum efficiency very quickly, so that the duration of pressure may be limited to a fractional part of a minute. This procedure makes it practicable to employ apparatus 90 such as the novel apparatus illustrated, in the use of which the duration of the heavy-pressure period and the number of heels built during a given pressure period are so proportioned that, just as soon as one batch 95 of heels has been pressed, they may be immediately removed and replaced with heels comprising a like number of lifts, which heels have been built concurrently with said pressure period, thus utilizing the machine to the best advantage. The application of 100 the heavy pressure to the heels is preferably made to follow immediately after the heels have been built. This insures the reduction of the paste layers to a very thin, evenly distributed film of adhesive, which gives the 105 most efficient union. The heavy pressure, applied immediately, also facilitates the penetration of the heel material by the liquid of the paste.

An important factor in the efficient production of heels provided by this invention 110 consists in the kind of paste employed for sticking the lifts together. It has been found that markedly superior results are obtained by employing a quick-setting paste 115 having an ingredient, such for example as sodium bicarbonate, sal soda, or borax, giving it a strong alkaline reaction, the paste advantageously having a starch base such as corn or potato dextrines, or tapioca flour. As herein exemplified, such an alkaline paste is made from the well-known commercial "Eureka" gum, by the addition of as much as one part of an alkaline ingredient such as sodium bicarbonate, sal soda, borax and the like, to a mixture of four parts of Eureka 120 gum in thirty-two parts of water, the whole being cooked. Distinctly beneficial results contributing 125 to the superior quality of the heels produced 130

result from such use of an alkaline ingredient in the substantial quantity indicated. It increases the fluidity and penetrating properties of the paste so that it is absorbed into the lifts rapidly and dries or sets quickly; it stabilizes the paste and produces a permanent and homogeneous emulsion which retains the adhesive portions in suspension so that the paste is especially effective; it acts upon and modifies the surface glaze of leatherboard lifts and thus permits of a more ready penetration of the paste into the pores; and also it so generally improves the properties of the paste and peculiarly adapts it for advantageous and expeditious use in the heel-building art, particularly when employed in connection with the heavy range of pressures contemplated by the present invention, that great economies result in the amount of paste employed. Furthermore, while the superiority of such a paste is very marked, whatever treatment is employed to set the paste and obtain adhesion between the lifts, this kind of paste is peculiarly efficient when heavy pressures such as contemplated by the present invention are employed. As demonstrated in many instances, the adhesiveness of the paste has even exceeded the strength of the heel lift material, so that the body portions of the lifts would tear before there would be any separation of the lifts.

These and other objects and features of the invention will be readily understood from the following description, read in connection with the accompanying drawings, in which:

Figure 1 is a view in front elevation of a duplex machine constructed in accordance with the present invention; Fig. 2 is a view in side elevation, looking from right to left in Fig. 1; Fig. 3 is a detailed view of one of the heel form supports, showing particularly an auxiliary means that may be employed for draining off any excess of paste that may accumulate in the heel form; Fig. 4 is a view, partially in plan and partially in section on the section line 4—4 of Fig. 2, showing particularly the driving mechanism of the machine; Fig. 5 is a view in side elevation, looking from left to right in Fig. 1, of the lower portion of the machine and showing particularly the automatic control mechanism for the main clutch, a portion of the apparatus being broken away for the sake of clearness; Fig. 6 is a detailed plan view of a portion of the frame; Fig. 7 is an enlarged sectional plan view taken on the section line 7—7 of Fig. 8; Fig. 8 is an enlarged view in front elevation of one of the heel form supports and the mechanism for effecting its actuation; Fig. 9 is a view, partially in side elevation and partially in section on the line 9—9 of Fig. 8, and showing the support in

its raised pressure-applying position; Fig. 10 is a view, partially in side elevation and partially in section on the line 10—10 of Fig. 8, showing the support in its raised heel assembling or building position; Fig. 11 is an enlarged view in front elevation of one set of heel forms in cooperative pressing relation to the stationary pressure means; Fig. 12 is a plan view of the apparatus shown in Fig. 11; Fig. 13 is a sectional view on the section line 13—13 of Fig. 11; and Fig. 14 is a plan view of one of the heel forms mounted upon the upper end of one of the heel form supports.

Referring to the drawings, the preferred embodiment of the invention illustrated therein comprises, in general, a frame 20 upon which the component mechanisms of the machine are mounted; lift holding means 22 having bins or lift holders 24 adapted to contain lifts in loose bulk that are segregated in accordance with their characteristics; pressure means comprising a plurality of sets of stationary upper pressure members 26 against which the heels are pressed while being subjected to pressure; pasting means 28 by means of which the lifts are coated with paste; a plurality of sets of movable duplex heel forms 30 into which the heels are progressively built and in which they are subsequently pressed by being brought into cooperative pressing relation with the stationary pressure means; a pair of movable heel form supports 32 upon which the heel forms 30 are mounted; a pair of vertically reciprocating carriages 34 for supporting and reciprocating the supports 32 and heel forms 30; an actuating mechanism including cams 36 for alternately actuating the carriages 34, supports 32 and heel forms 30 to and from their respective operating positions; a plurality of ejecting devices including plungers 38 for releasing the heels from the heel forms after they have been pressed; a clutch controlling mechanism including a rotatable clutch arm 40, a control lever 42, a foot treadle 44 and control cam 46, by means of which the starting and stopping of the machine is governed; and a safety device or lock 48 for preventing the starting of the machine except under the control and at the will of the operator.

The supporting frame of the machine comprises a plurality of lower side pedestals 50 (Figs. 1 and 2) upon which is mounted an upper frame member 52 embodying an upper horizontal plate 54 that, in plan, is of the general form of a letter **E**, as shown in Fig. 6. The upper frame member 52 is secured to the side pedestals 50 by means of the outermost of four stationary vertical rods 56, the lower ends of which project through adjacent flanges of the frame member 52 and pedestals 50 and are provided

with nuts 58 by which the component parts of the frame are firmly bolted together. The adjacent inner rods 56 are supported upon a middle rib 60 of the upper frame member 52 by being bolted thereto in the same general manner.

The driving mechanism of the machine is carried by the lower pedestal members 50 and comprises a power shaft 62 (Figs. 4 and 5) suitably journaled therein and which is provided at one end with a pulley 64 loosely mounted upon the shaft and adapted to be constantly driven by means of a belt (not shown) or other suitable means. A clutch of any well-known form embodying the rotatable clutch arm 40 is employed for connecting and disconnecting the pulley 64 to and from the power shaft 62. The opposite end of the shaft 62 carries a pinion 66 that meshes with a gear 68 fixed to the corresponding end of a shaft 70, the ratio of the gearing, in this instance, being four to one, so that for every two revolutions of the power shaft 62, the shaft 70 rotates through one half of the revolution. The shaft 70 constitutes the cam shaft of the machine and is provided with a pair of similar actuating cams 36 that are alternately or oppositely arranged, and also with the clutch control cam 46, the function of which will be hereinafter fully disclosed.

The lifts, which may be of leather, leather-board or analogous heel-lift material, from which the heels are to be built are segregated according to their characteristics and contained in the several lift holders 24 of the holding means 22 which is conveniently supported upon a plurality of rearwardly extending brackets 72 that are secured to the frame of the machine. The front openings of the several lift holders from which the lifts are removed are constructed and arranged to allow a plurality of lifts to be removed at once and are preferably sufficiently large to permit the introduction of both hands of the operator at the same time. In order that all of the lift holders shall be located within easy reaching distance of the operator, the lift holders are arranged in two tiers, the one above the other.

In the illustrated process of building heels, the operator selects, picks up and removes two lifts at a time from the proper lift holder 24, preferably, one with each hand. It being desirable to have the bottom surface of the lowermost lift in a heel free of paste, the first two lifts removed from the lift holding means are not pasted but are deposited directly into the duplex heel forms 30 by substantially concurrent and similar movements of the operator's hands. Subsequently two other lifts are removed in the same general manner from the proper lift holder after which the operator applies paste to the lower faces thereof. In the

machine illustrated, this is accomplished by wiping the two lifts substantially concurrently across the pasting means 28, one lift being held in each hand. The pasting means 28 is conveniently located below and immediately in front of the lift holding means.

Referring particularly to Figs. 11, 12 and 13, the pasting means 28 comprises a shallow tank 74 containing a body of paste in 75 which is immersed a paste brush or pad 76. This pasting means 28 is so constructed and arranged as to enable the operator to conveniently apply paste to two lifts at a time and preferably extends throughout a substantial length of the lift holder case 22, in order that the lifts when taken from even the more remote lift holders may be brought into contact therewith directly and quickly and with a minimum of unnecessary movement. The paste tank 74 rests upon a plurality of brackets 77 which are secured to a pair of yoke members 78 that are carried at the upper ends of each pair of the four vertical rods 56 and upon which are mounted the stationary upper pressure members 26.

In order to remove any excess of paste upon the lifts and to distribute the paste evenly over their faces, a plate or shelf 80 is suitably mounted upon the forward edge of the paste tank 74, said plate being provided with a downwardly inclined rearward portion 82 extending into the tank 74 and a substantially horizontal forwardly projecting portion 84. After the lifts are wiped over the paste pad 76, they are drawn up the inclined surface 82 and across the horizontal surface 84 of the plate 80 by substantially concurrent movements, while being pressed against the plate throughout 100 the operation. As the lifts pass over the inclined surface 82 of the plate 80 under pressure, the excess paste is removed and is allowed to return to the paste tank 74, while the pressure of the lifts against the plate 80 110 during the continued forward movement of the lifts across the horizontal portion 84 thereof serves to spread out and evenly distribute the paste over the faces of the lifts.

As already stated, the paste is preferably formed from an aqueous solution of a commonly employed commercial heel-building gum of a starch base which is rendered alkaline by the addition of a sufficient quantity of bicarbonate of soda, or the like to produce a distinctly alkaline reaction.

Having properly coated the pair of lifts with paste in the manner described, one lift being always retained in and manipulated by each hand, the operator next deposits the pasted lifts substantially concurrently with the respective hands upon the previously assembled dry lifts in the pair of heel forms 30 comprising one set, or unit of the machine. This set of heel forms 30 occupies a 130

- forward position, as shown in Figs. 1 and 2, in which the forms are readily accessible to permit the operator to assemble or deposit the pasted heel lifts therein. Other pairs of lifts are subsequently removed from the lift holding means, pasted and assembled progressively into the duplex heel forms in a similar manner until the heels are built up to the required height.
- 10 There are two sets of heel forms 30, and inasmuch as they are of like construction, it is only necessary to describe a single heel form. Each heel form, as shown particularly in Fig. 14, comprises a base portion 88 having a plurality of upwardly extending fingers 90 that are so located and shaped as to conform to the ultimate shape of the heel to be assembled or built therein. The heel forms 30 of each set are detachably mounted 15 by means of screws 92 to the upper end of one of the heel form supports 32, a member 94 of suitable material to which the paste will not readily adhere being interposed between the base portion 88 of the heel form 20 and the upper surface of the support 32. In the event of an accumulation of paste upon the heel forms 30 during the heel building operations, the excess is carried away through the agency of draining devices 25 which comprise troughs 91 (Fig. 3) secured to the upper ends of the respective supports 32. These troughs 91 respectively deliver the excess paste into the upper ends of a pair of tubular conductors 93 suitably mounted upon the respective supports 32 and extending downwardly into proximity to a receptacle 95 mounted at the lower portion of the machine.
- 30 After two heels are completed in the set of duplex heel forms 30 occupying its lift-receiving or assembling position, these heels immediately are transferred together to a pressure-applying station where they are subjected to heavy pressure simultaneously 35 during the concurrent assembly of two other heels in the other set of heel forms. For this purpose, the two sets of heel forms 30 are mounted upon the heel form supports 32 by which they are actuated alternately from a forward heel building or lift-receiving position to a rearward pressure-applying position in which they are held in cooperative pressing relation to the pressure means and, more specifically, to their corresponding fixed pressure members 26. The supports 32 are similar in construction and each is pivotally mounted at its lower end upon a stud 96 (Figs. 8 and 10) that is carried by forwardly and downwardly projecting extensions 98 forming parts of the carriage 34, which is provided at the front with a central open recess to permit of the reception of the lower portion of the support 32. Each carriage 34 further embodies a plurality of recessed lugs 100 that are adapted to slide 40 upon two of the stationary vertical rods 56, which extend upwardly through the upper plate 54 of the frame member 52 and upon which one of the yokes 78 carrying the upper pressure members 26 is adjustably mounted. 45 The upper ends of each pair of vertical rods 56 are threaded and loosely project through openings in the respective ends of the yoke 78 which is supported in position by means of fingers 102 secured thereto and projecting loosely into grooves 104 provided in a pair of manually operable adjusting nuts 106 that are threaded upon the upper ends of the rods 56. By suitably adjusting the nuts 106, the machine may be adapted to subject heels 50 of any height to any desired degree of heavy pressure.
- 55 The respective pressure members 26 of each set are mounted for limited adjustment both laterally and back and forth, that they may be positioned to properly align with the heel forms 30 with which they cooperate. For this purpose, the pressure members 26 are loosely mounted upon a rod 108 and are maintained in position by means of a plurality of set screws 110 that project downwardly through the yoke member 78 and into engagement with oppositely extending flanges 112 constituting integral parts of the pressure members 26. The set screws 110, 60 not only serve to definitely position the pressure members 26 against sidewise movement, but also may be adjusted so as to cause the lower pressing surfaces of the pressure members to assume the proper inclination to accommodate heels of any desired inclination or wedge form. Moreover, the set screws 110 are also utilized to take the upward thrust during the pressing operation, thereby relieving the supporting rod 108 from 65 undue stress.
- 65 The back and forth adjustment of the pressure members 26 is accomplished by mounting the respective ends of the rod 108 in a plurality of slides 114 that are slidably mounted within suitable grooves in the lower face of the yoke member 78, and set screws 116 are employed to definitely position the slides 114 after they have been adjusted to their proper positions.
- 70 As already mentioned, there are two sets of heel forms 30 and pressure members 26, as well as two heel form supports 32, thus constituting a machine of multiple or twin construction, one unit being adapted to receive the component lifts of two heels during the heel building operation, while the other unit occupies a pressure-applying position to maintain pressure upon the previously built heels while the paste is setting, and while two other heels are being built in the first unit. Each unit is duplex in arrangement, being provided with two heel forms in which two heels are built substantially concurrently.

- 130

Moreover, the construction and relative arrangement of the sets of heel forms, the pasting means and the lift holding means is such that lifts may be removed from the holding means, pasted, and assembled into the heel forms by substantially continuous movements of the lifts in the same general direction.

The mechanisms for actuating the several units from one operative position to another, and for subjecting the heels to pressure include the cams 36 upon the cam shaft 70, and inasmuch as these operating mechanisms are similar in construction and differ only in their angular positions or time relation, only one of said actuating mechanisms will be described.

Each cam 36 is provided with two oppositely disposed high portions 116 and is adapted to cooperatively engage a roll 118 that is carried by the stud 96 mounted upon the movable carriage 34. As the actuating cam 36 is rotated from either of the positions shown in Figs. 9 and 10, the carriage 34 is reciprocated vertically, being moved downwardly and then upwardly once, for each half revolution of the cam, thereby lowering and then raising the support 32 and set of heel forms 30 mounted thereon. In order to bring the set of heel forms 30 from its raised lift-receiving position, as indicated in Fig. 10, into pressure-applying position in cooperative pressing relation with the pressure means, as illustrated in Fig. 9, it is also necessary to provide means for swinging the support 32 and heel forms 30 backwardly into vertical alignment with the upper pressure members 26 prior to the upward movement of the carriage and heel forms effected by the cam. Therefore, a downwardly extending actuating arm 120 is firmly secured to the lower portion of the support 32 and projects into the path of movement of a cam block 122 that is secured to the side of the cam 36. As the cam 36 is rotated, the carriage 34 and heel forms 30 are first lowered from their lift-receiving positions, away from the operator's fingers, until the cam block 122 is brought into engagement with the arm 120, whereupon the support and heel forms are swung backwardly into alignment with the pressure means, so that upon the upward movement of the carriage 34, effected by the cam 36, the heel forms 30 are brought into pressing relation with the upper pressure members 26 and the heels contained therein are thus subjected to pressure substantially concurrently. This pressure is heavy, and preferably within the range of pressures hereinbefore indicated, the desirable pressure being dependent upon the nature of the paste, the duration of the application, and other operating conditions.

As the support and heel forms are thus

swung into pressing alignment with the pressure means, a locking plate 124 secured to the support is brought into engagement with a portion 126 of a stop 128 that is adjustably fixed to one of the vertical rods 56. Before the cam block 122 disengages the actuating arm 120, the cam 36 becomes operative to raise the carriage 34 and support 32 sufficiently to cause the locking plate 124 to be projected upwardly through a notch 130 in the stop member 128, thereby maintaining the heel forms 30 in vertical alignment with the pressure members 26, both during the remainder of the upward movement thereof and subsequently during the initial portion of the retracting downward movement after pressure has been applied.

The heels in the respective heel forms 30 are left under constant heavy pressure for a period sufficient to permit the paste to set, which depends upon various conditions, among which are the character of the paste and the amount of pressure employed. The time required for effecting satisfactory pressure of heels in the described machine, when the novel paste herein disclosed is employed, has been found to be substantially the time required to build in multiple, by using the two hands of the operator in the manner described, a pair of eight-lift heels. It is contemplated that this machine shall also be used in the manufacture of low heels, such as men's heels, which require fewer lifts and therefore less time to assemble. An extreme example of low heels in the manufacture of which this machine has been used successfully is found in two-lift slipper heels. In this use, a number of heels are built concurrently, one on top of another, in each one of a pair of heel forms. That is, to continue the above illustration, if the heel forms are each adapted to hold an eight-lift heel and two-lift heels are to be built, as many as four two-lift heels may be built one on top of another in each of the pair of forms concurrently by the hands of the operator. Or, alternatively, the same number of heels may be built concurrently in two pairs of forms during a pressure period. The important thing is that the pressure period and the number of heels built during that period are so proportioned that while the lifts of one batch of heels are being pressed, a like number of lifts will be built into heels, a pair or a plurality of pairs of heels being built during each heavy-pressure period, according to the height of the heels, and immediately put under heavy pressure, with the result that the building and pressing are carried on alternatively by the use of the duplex machine construction herein described.

Subsequent to the application of pressure, the heel forms 30, support 32 and carriage 34 are permitted by the cam 36 to be low-

ered out of pressing relation, although maintained temporarily in vertical alinement with the pressure members 26 by the cooperative action of the locking plate 124 and notched stop member 128. During this lowering movement, the pressed heels in the heel forms are released and partially ejected by means of the ejecting plungers 38.

Referring particularly to Figs. 11 and 13, 10 each heel form 30 is provided with an ejecting plunger 38 that is fixed to a yoke 134 and projects loosely through a suitable opening in the upper end of the support 32. The ejector yoke 134 is supported in position by means of a pair of adjustable rods 136, the upper ends of which are threaded into the support 32 and the lower ends of which project loosely through openings in the yoke 134 and are provided with suitable 15 heads upon which the yoke rests. These rods 136 are surrounded by a pair of coiled springs 138 that normally serve to hold the yoke 134 and ejector plungers 38 in their 20 lowermost inoperative positions. In order 25 to cause the ejector plungers to function to release the heels during the retracting downward movement of the heel forms, the yoke member 134 is provided with a central recess 140 in which is pivotally mounted a 30 pawl 142 that is normally maintained in the position shown in Fig. 13, by means of a spring 144. As the support 32 and heel forms 30 are retracted from pressure-applying 35 position, the pawl 142 is brought into engagement with a projecting stop member 146 that is secured to the upper frame member 52, thereby arresting the downward movement of the ejector plungers and causing them to be projected upwardly relative 40 to said heel forms and into releasing engagement with the pressed heels therein.

Immediately subsequent to the releasing operation, the locking plate 124 is lowered out of engagement with the notched stop 45 member 128, and a plunger 150 actuated by a coiled spring 152 operates upon a portion of the support 32 to force it and the heel forms forwardly out of alinement with the upper pressure means. A rigid stop is provided 50 for the purpose of limiting the forward movement of the support 32, and this stop comprises a plate 154 that is secured to the support and which is brought into engagement with the stop member 128. However, in order to avoid any undue shock to the apparatus, a cam block 156 is secured to the actuating cam 36 and functions to engage the actuating arm 120 during the forward movement of the support and heel 55 forms to control and retard this movement.

After the heel forms have been swung forwardly and have also reached their lowermost positions, the continued rotation of the actuating cam 36 serves to raise the carriage 34 and therefore the support 32

and heel forms 30 until said heel forms are brought into their raised and forward heel building positions out of alinement with the pressure means.

The proper movements of the heel forms 70 30 are effected by locating the cam block 122 with reference to the high portions 116 of the cam 36 so that said block cooperates with the actuating arm 120 only once during each complete revolution of the cam. Thus, just 75 prior to one upward movement of the carriage 34 and heel forms 30, effected by one high portion of the cam 36, the cam block 122 will swing the heel forms backwardly into the vertical plane of the pressure means, 80 whereas on the next elevation of the carriage and heel forms, effected by the other high portion of the cam 36, the cam block 122 will not cooperate with the arm 120 and, as a consequence, the heel forms 30 occupying 85 their forward positions will be elevated into a position to permit heels to be assembled or built therein.

While it is not necessary that the heel forms occupy a raised position during the 90 building operation, it is found desirable for the reason that the subsequent lowering movement thereof, preparatory to being swung inwardly and raised to pressure-applying position, serves to withdraw the 95 heel forms from the operator's fingers and thus prevents the fingers from being carried inwardly and injured during the pressing operation.

As already stated, the machine is of twin 100 construction, being provided with two units of heel forms, pressure members, jacks and carriages, which units are similar in construction and operation, except that the respective units are operated in opposition or 105 alternation, the one unit occupying its pressure-applying position while the other unit occupies a position in which the heel forms are presented for the convenient assembly of heels. This alternate operation of the 110 respective units is accomplished merely by locating the respective actuating cams 36 and cam blocks 122 and 156 180 degrees apart, upon the cam shaft 70.

The machine is power driven, as already 115 described, but is under the control of the operator through the agency of a clutch of any well-known construction, which therefore need not be described, and which embodies as a component element thereof, the 120 rotating clutch arm 40 which is constructed and arranged so that when it is free to rotate with the constantly driven pulley 64, it establishes an operative connection between said pulley and the power shaft 62, and when 125 held against rotation, it effects the disconnection of the clutch and therefore arrests the operation of the machine.

The machine is of the single cycle type, 130 being thrown into operation under the con-

trol of the operator and being automatically brought to rest by the disconnection of the clutch, after a single cycle has been performed. This automatic interruption of the 5 operation is timed to occur when either one of the units or sets of heel forms is in pressure-applying position and the other set is in heel building or lift-receiving position.

In the illustrated machine, this result is 10 secured by means of the two-armed V-shaped control lever 42 which is mounted upon a rock shaft 160 to which is attached the treadle 44. A spring 162 normally tends to hold the treadle in its upward position and 15 one of the arms of the V-shaped control lever 42 in position to be engaged by the rotating clutch arm 40, while the other arm thereof is adapted to cooperate with the control cam 46 on the cam shaft 70. By reason 20 of this arrangement, when two heels have been built in the exposed set of heel forms, the operator merely has to depress the treadle 44, thereby releasing the clutch arm 40 and permitting the clutch to be thrown 25 into action to start the machine into operation. As the control cam 46 rotates, it maintains the cam-engaging arm of the V-shaped control lever 42 out of the path of movement of the rotating clutch arm 40 until the cam 30 shaft and control cam 46 have rotated through 180 degrees, whereupon the spring 162 returns the control lever 42 into position to be engaged by the rotating clutch arm 40. Thereupon, the clutch is disconnected and 35 the machine brought to rest with one of the units or sets of heel forms in pressure-applying position and the other in lift-receiving or heel building position.

For the purpose of preventing the accidental operation of the treadle 44, the lock or 40 detent 48 is provided, and it normally occupies the position shown in Fig. 5, in which it serves as a stop to prevent the depression of the treadle and, consequent starting of the 45 machine until it has been manually released. This locking detent 48 is located on the side of the machine and is adapted for vertical sliding movements, the upper end thereof being pivotally attached to the inner end of a 50 control lever or handle 164 that is rotatably mounted upon a pin 166 carried by a bracket 168 that is secured to the frame of the machine. A torsion spring 170 surrounds the pin 166 and operates in such manner as to 55 normally hold the operating handle 164 in its raised position and the locking detent 48 in its lowered operative position. When the machine is to be started into operation, the operator merely has to depress the control handle 164 to release the locking detent 48, after which the treadle 44 may be depressed, and the machine connected to the 60 source of power by the clutch. As soon as the machine starts into operation, the cam-engaging arm of the V-shaped control lever

42 serves to retain the locking detent 48 in its upper inoperative position until a half revolution of the cam shaft and control cam 46 has taken place, when the machine is automatically brought to rest in the manner described and the locking detent is released and permitted to be thrown into its normal locking position, by the torsion spring 170.

Although for illustrative purposes the method and apparatus of the present invention have been set forth in greater or less detail, it will be understood that the invention is not so restricted and that many of the advantages and benefits thereof may be derived from methods and machines differing considerably from those specifically described without departing from the spirit and scope of the invention. Therefore only such limitations should be imposed as are indicated in the appended claims.

Having thus described the preferred method and embodiment of the invention, that which is claimed as new is:—

1. A method of heel manufacture which comprises building heels in multiple by substantially concurrent and similar operations of the two hands of an operator.
2. A method of heel manufacture which comprises building heels in multiple substantially concurrently by substantially completing at each of several stations in turn operations performed by the two hands of an operator upon a plurality of heels, whereby the attention and effort of the operator are directed to the operation being performed at each station before being transferred to the succeeding station.
3. A method of heel manufacture which comprises building pasted heels in multiple by substantially concurrent and similar operations of the two hands of an operator, the lifts of each heel which are to be pasted having paste applied thereto while still held in the hands of the operator.

4. A method of heel manufacture which comprises building heels in multiple substantially concurrently and then subjecting said heels to pressure substantially concurrently while other heels are being built.

5. A method of heel manufacture which comprises building heels in multiple substantially concurrently, transferring the heels together to a pressure station, and subjecting them to pressure substantially concurrently while other heels are being built.

6. A method of heel manufacture which comprises building heels in multiple substantially concurrently by successive operations including picking up a plurality of lifts, applying paste thereto, and assembling the lifts into heel forms, all by substantially continuous movements of the lifts in the same general direction.

7. A method of heel manufacture which comprises building heels in multiple in a

pair of sets of heel-forms, each comprising two heel-forms, and including building a plurality of heels substantially concurrently in the heel-forms of one set, one heel by 5 each hand, subjecting to pressure the heels built in the heel-forms of the first set, and during the continued application of pressure to the heels in the first set, building two other heels in a similar manner in the 10 heel-forms of the second set.

8. A method of heel manufacture which comprises building heels in multiple by successive manual operations, each performed substantially concurrently on two heels by 15 an operator and including selecting and picking up two lifts, and depositing the lifts into a plurality of heel-forms.

9. A method of heel manufacture comprising building heels in multiple by successive operations, each performed substantially concurrently by the two hands of an operator upon a plurality of heels and including picking up two lifts, one in each hand, and depositing said lifts, one by each 25 hand, into a pair of adjacent heel-forms.

10. A method of heel manufacture which comprises building heels in multiple by successive manual operations, each performed substantially concurrently on two heels by 30 an operator and including selecting and picking up two lifts, applying paste thereto, and then depositing the lifts into a pair of heel-forms.

11. A method of heel manufacture which comprises selecting and picking up two lifts substantially concurrently, depositing them substantially concurrently into a plurality of heel-forms, similarly selecting and picking up other pairs of lifts, applying paste thereto, and assembling them two at a time 35 into the heel-forms.

12. A method of heel manufacture comprising building heels in multiple by successive operations, each performed substantially concurrently by the two hands of an operator upon a plurality of heels, including picking up two lifts, one by each hand, applying paste to all but the first two lifts, and then depositing the pasted lifts, one by 40 each hand, into a pair of heel-forms.

13. A method of heel manufacture comprising building heels in multiple by successive operations, each performed substantially concurrently by the two hands of an operator upon a plurality of heels and including picking up two lifts, one by each hand, applying paste thereto while still retained in the hands, and subsequently depositing the pasted lifts, one by each hand, 45 into a pair of adjacent heel-forms.

14. A method of heel manufacture which comprises building pasted heels in multiple by successive operations, each performed substantially concurrently upon a plurality 50 of heels and including the manual opera-

tions of picking up a plurality of lifts, applying paste thereto, and assembling the lifts into heels, and thereafter subjecting the heels to pressure, while other heels are built in a similar manner.

15. A method of heel manufacture comprising building heels in multiple by successive operations, each performed substantially concurrently by the two hands of an operator upon a plurality of heels and including picking up two lifts, one with each hand, applying paste thereto and spreading the paste thereon, all while retained in the respective hands, and then depositing the lifts, one with each hand, in separate piles 75 to form heels.

16. A method of heel manufacture which comprises building heels in multiple by successive manual operations, each performed substantially concurrently on two heels by 80 an operator and including picking up two lifts, applying paste to one face of each lift, spreading the paste by pressure against a flat surface and then depositing the pasted lifts into a pair of heel forms.

17. A method of heel manufacture which comprises picking up successive pairs of lifts, applying paste concurrently to one face of each lift of a pair, removing the excess paste from the pasted lifts by a wiping movement of the lifts over a surface 90 and then assembling the lifts into a pair of heels.

18. A method of heel manufacture which comprises passing successive pairs of heel lifts over a paste-applying member, concurrently distributing the paste and removing any excess thereof by pressure upon a flat surface, and assembling the lifts into a pair of 95 heels.

19. A duplex heel building machine having, in combination, pressure means, a pair of heel forms normally disposed in front of said pressure means and into which heels are built substantially concurrently, means 100 for effecting relative horizontal movement of said heel forms and said pressure means until they are in vertical alinement, and means for subjecting the heels to pressure substantially concurrently.

20. A duplex heel building machine having, in combination, pressure means, a pair of heel forms normally disposed in front of said pressure means and into which heels are built substantially concurrently, and means for effecting relative horizontal movement of said heel forms and said pressure means until they are in vertical alinement, and for effecting relative approaching movement thereof to subject the heels 115 to pressure substantially concurrently.

21. A duplex heel building machine having, in combination, stationary upper pressure means, a pair of movable heel forms normally disposed in front of said pressure 120 means, and means for effecting relative approaching movement of the movable heel forms to subject the heels to pressure substantially concurrently.

- means and into which heels are built substantially concurrently, means for actuating said heel forms into vertical alinement with the pressure means, and means for subjecting the heels to pressure substantially concurrently.
22. A duplex heel building machine having, in combination, two heel forms and lift holding means constructed and arranged for substantially concurrent removal of two lifts from the lift holding means and substantially concurrent building and assembling of heels in the heel forms, pressure means, and means for producing relative movements between said heel forms and said pressure means to first aline the forms and pressure means and then to subject the built-up heels to pressure substantially concurrently.
23. A duplex heel building machine having, in combination, lift holding means constructed and arranged for ready removal of a plurality of lifts substantially concurrently, two heel forms in which two heels may be built at the same time, pressure means for subjecting to pressure substantially concurrently the heels built in said forms, and means for moving the heel forms from a heel lift receiving and assembling position out of cooperative relation with the pressure means to a position in cooperative relation with the pressure means.
24. A duplex heel building machine having, in combination, lift holding means constructed and arranged for the ready removal of two lifts substantially concurrently, two heel forms into which two heels are completely built substantially concurrently, and pasting means disposed between the lift holding means and the heel forms and constructed and arranged for the application of paste to two lifts substantially concurrently.
25. A duplex heel building machine having, in combination, two heel forms, lift holding means and pasting means constructed and arranged relative to said heel forms to permit substantially continuous movements in the same general direction by the two hands of the operator from the lift holding means to the heel forms for applying paste to and assembling pairs of lifts, one by each hand, into the respective heel forms, pressure means, and means for effecting relative movements of the heel forms and pressure means for subjecting the built-up heels to pressure substantially concurrently.
26. A duplex heel building machine having, in combination, a plurality of lift holders each having a sufficiently large front opening to permit the introduction of both hands of the operator and the removal of two lifts at the same time, pasting means for applying paste to the lifts removed from said lift holders, and two heel forms into which the pasted lifts are deposited substantially concurrently.
27. A duplex heel building machine having, in combination, a plurality of lift holders each having a sufficiently large front opening to permit the introduction of both hands of the operator and the removal of two lifts at the same time, pasting means constructed and arranged to permit the operator to apply paste substantially concurrently to two lifts, and two heel forms into which the pasted lifts are deposited substantially concurrently.
28. A duplex heel building machine having, in combination, lift holding means constructed and arranged for ready removal of two lifts substantially concurrently, means disposed below and in front of the lift holding means and constructed and arranged to permit the operator to apply paste substantially concurrently to two lifts, and two heel forms disposed below and in front of said pasting means into which the pasted lifts are deposited substantially concurrently.
29. A duplex heel building machine having, in combination, two supports, each carrying two heel forms into which two heels are built substantially concurrently, pressure means, and means for moving one support to transfer two heels into pressing relation with said pressure means and hold them under pressure while the other support is moved into heel lift assembling position.
30. A duplex heel building machine having, in combination, two supports, each carrying two heel forms, lift holding and pasting means common to all the heel forms and constructed and arranged to facilitate the filling of the heel forms in pairs with pasted lifts, pressure means, and means for moving one support to carry the heels in one pair of heel forms into pressing relation with said pressure means and hold them under pressure, while the other support is actuated to carry the other pair of heel forms into position to be filled.
31. A heel building machine having, in combination, stationary pressure means, two movable heel forms into which heels are built and severally adapted to cooperate with said pressure means, said heel forms being movable back and forth from the vertical plane of said pressure means, and means for controlling and actuating said movable heel forms to cause them to move into cooperative pressing relation with said pressure means alternately.
32. A duplex heel building machine having, in combination, a pair of sets of heel forms, each comprising two heel forms in which two heels may be built at the same

time, means for subjecting the heels in one set of heel forms to pressure substantially concurrently, and means for effecting relative movements between the heel forms of each set and pressure means to cause each set of heel forms to be alternately in heel lift receiving and assembling relation and in pressure applying relation.

33. A duplex heel building machine having, in combination, a pair of sets of heel forms, each comprising two heel forms in which two heels may be built at the same time, pressure means, and means for relatively moving the heel forms of the two sets to cause said pressure means to apply pressure to the heels built in one set of heel forms while the other set of heel forms is in position for the reception and assembling of heel lifts therein.

34. A duplex heel building machine having, in combination, lift holding means having a sufficiently large front opening to permit the introduction of both hands of the operator and the removal of two lifts at the same time and a pair of sets of heel forms, each comprising two heel forms in which two heels may be built at the same time, and means for concurrently moving both sets of heel forms to such positions that the heels built in one set can be subjected to pressure while the other heel forms can have heels built in them.

35. A duplex heel building machine having, in combination, lift holding means constructed and arranged for ready removal of a plurality of lifts substantially concurrently, a pair of sets of heel forms, each comprising two heel forms in which two heels may be built at the same time, pressure means, and means constructed and arranged to actuate said sets of heel forms so that the heel forms of one set are out of cooperative relation with the pressure means and in heel lift receiving and assembling relation while the heel forms of the other set are in cooperative relation with the pressure means.

36. In a heel building machine, the combination of means for pressing together the lifts of a freshly pasted heel, a form into which lifts may be assembled manually, and a support upon which said form is mounted, said support being constructed and arranged to swing in a vertical plane about a pivot beneath the form from a position in front of the pressing means to a position in which a heel in the form is in co-operative relation to the pressing means.

37. A heel building machine having, in combination, means for applying paste to the component lifts of a heel, stationary pressure means, and a movable heel form, in which a pasted heel is built, adapted to be actuated from a lift-receiving position out of alinement with said pressure means to a position in cooperative pressing rela-

tion therewith and toward said pressure means, whereby the pasted heel built in said heel form is subjected to pressure.

38. A heel building machine having, in combination, stationary upper pressure means, a movable heel form normally occupying a forward position to permit a heel to be built therein, and means for actuating said heel form into vertical alinement with said upper pressure means and then raising said heel form into cooperative pressing relation therewith to subject the heel to pressure.

39. A heel building machine having, in combination, stationary upper pressure means, a vertically reciprocable heel form in which heels are built and pressed, normally occupying a position out of vertical alinement with the upper pressure means to permit a heel to be built therein, and means for effecting the vertical alinement of said heel form and pressure means on each alternate upward movement of said heel form and for maintaining the heel form and pressure means out of alinement on the other alternate upward movements thereof.

40. A heel building machine having, in combination, stationary upper pressure means, a movable heel form normally occupying a forward raised position to permit a heel to be built therein, and actuating means for lowering said heel form, moving it into vertical alinement with said upper pressure means and then raising said heel form into pressing relation therewith to subject the heel to pressure.

41. A heel building machine having, in combination, stationary pressure means, a vertically movable carriage, and a heel form, in which heels are built and pressed, mounted upon said carriage for forward movement from the vertical plane of said pressure means when said pressure means and said heel form are out of cooperative pressing relation.

42. A heel building machine, having, in combination, stationary pressure means, a vertically movable carriage, a movable heel form, in which heels are built and pressed, mounted upon said carriage for forward movement from the vertical plane of the pressure means to permit a heel to be built therein, and means for moving the heel form into vertical alinement with the pressure means to cause the heel form and pressure means to subject the heel to pressure when the carriage is moved upwardly.

43. A heel building machine having, in combination, lift holding means, stationary upper pressure means disposed below and in front of said lift holding means, pasting means carried by said pressure means and disposed between it and the lift holding means, a movable heel form normally occupying a position below and in front of

said pressure means to permit the building of heels therein, and means for actuating said heel form into cooperative pressing relation with said pressure means to subject 5 the heel to pressure.

44. A heel building machine having, in combination, a movable heel form into which lifts are assembled to form a heel, a stationary pressure means, means for moving said heel form from a lift assembling position out of alinement with said pressure means to a position in cooperative relation with said pressure means, means for moving the form toward said pressure means, and resilient means for moving said heel form out of cooperative relation with said pressure means.

45. A heel building machine having, in combination, a movable heel form into which lifts are assembled to form a heel, a stationary pressure means, means for moving said heel form from a lift assembling position out of alinement with said pressure means to a position in cooperative relation with 25 said pressure means, resilient means for moving said heel form out of cooperative relation with said pressure means, and means for controlling and retarding the movement of the heel form out of cooperative relation with said pressure means.

46. A heel building machine having, in combination, stationary upper pressure means, a movable heel form normally occupying a forward position to receive the component lifts of a heel, means for actuating said heel form into cooperative pressing relation with said pressure means, means for moving the heel form toward said pressure means, to subject the heel to pressure, means for restoring the heel form to its initial normal position, and means actuated during the restoring movement for releasing the pressed heel in the heel form.

47. A heel building machine having, in combination, stationary upper pressure means, a movable heel form, in which heels are built and pressed, normally occupying a position out of the vertical plane of the pressure means to permit a heel to be built therein, means for moving said heel form into vertical alinement with the pressure means and into cooperative pressing relation thereto to cause the heel to be subjected to pressure, resilient means for returning the heel form to its normal position, and guiding means for maintaining the heel form in vertical alinement with the pressure means against the action of said resilient means while the heel form is being moved into and out of pressing relation with said pressure means.

48. A heel building machine having, in combination, lift holding means, pasting means, a plurality of stationary guide rods, 65 a stationary upper pressure member mount-

ed on said rods, a vertically reciprocable carriage guided by said rods, and a heel form, into which heels are built, pivotally mounted upon said carriage for back and forth movements into and out of the vertical plane of 70 said pressure member.

49. A heel building machine having, in combination, pressure means, pasting means comprising a paste tank and a plate or shelf having its rear portion inclined downwardly toward said tank and its forward portion extending substantially horizontally, a heel form positioned in front of said pressure means to permit heels to be built therein, and means for moving said pressure means 80 and said heel form relatively into cooperative pressing relation to subject the heel to pressure.

50. A heel building machine having, in combination, a paste tank, a paste pad immersed in said tank across which the lifts are wiped by the operator, a plate or shelf having its rear portion inclined downwardly toward the tank and its forward portion extending substantially horizontally, said 90 plate or shelf serving to remove the excess of paste and distribute the remaining paste on said lifts as they are wiped over it, and a heel form into which the pasted lifts are deposited.

51. A heel building machine having, in combination, pressure means, a heel form normally out of vertical alinement with said pressure means and in which heels are built, means for effecting relative movements of 100 said pressure means and said heel form to align them and then subject the heel to pressure and to cause the heel form to lie out of alinement with said pressure means and in position for the ready assembling of a heel therein, power mechanism for driving the machine, and means for interrupting the driving mechanism automatically to stop the machine when the pressure means and heel form are out of alinement.

52. A heel building machine having, in combination, stationary upper pressure means, a vertically reciprocable heel form mounted to move back and forth from the vertical plane of the pressure means, means 115 for actuating said movable heel form towards and from the vertical plane of said pressure means, mechanism including a clutch for normally driving the machine, and automatic means for disconnecting the 120 clutch to stop the machine when the movable heel form is out of vertical alinement with said pressure means.

53. A method of heel manufacture which comprises building a heel with an adhesive 125 interposed between the component lifts thereof and subjecting the heel immediately to a heavy pressure in the neighborhood of 1600 lbs. for a fractional part of a minute.

54. A method of manufacture of pasted 130

heels including leatherboard lifts which comprises chemically modifying the surface glaze of the lifts by treatment with an alkali, applying an adhesive substance to the lifts, assembling the lifts into a heel, and immediately thereafter subjecting the heel to a very heavy pressure.

55. A method of manufacture of pasted heels including leatherboard lifts which comprises simultaneously treating the lifts with an adhesive and with an alkali in sufficient quantity to modify the surface glaze of the lifts and permit rapid penetration of the adhesive, then promptly assembling the lifts 10 into a heel and immediately subjecting the heel to a very heavy pressure.

56. The method of making pasted and pressed heels, which consists in coating lifts of a pair of heels with a quick-setting alkaline paste and assembling the heels substan- 15

20

tially concurrently on holders, subjecting the pair of heels to heavy pressure while the heels of another pair are being assembled, and then removing the first pair from said holders and building another pair on the 25 same holders while the heels of the second pair are being pressed.

57. The method of making pasted and pressed heels, which consists in coating lifts for a plurality of heels with a quick-setting alkaline paste, assembling heels in pairs, and subjecting the heels so assembled simultaneously to heavy pressure, the duration of the pressure period and the number of heels built during a given pressure period being 30 so proportioned that while the lifts of one batch of heels are being pressed, the same number of lifts will be assembled into heels. 35

WILLIAM HUBBARD.
